DESIGN FOR A DRESS

Anne Rebhuhn, New York, N. Y.

Application December 18, 1939, Serial No. 88,967

Term of patent 3½ years

To all whom it may concern:

Be it known that I, Anne Rebhuhn, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The design is characterized by the combination on the specific dress disclosed of the specific blouse portion having a square-cut, cord-bound neckline with rows of shirring extending from each lower corner of the square neck down the front to the matching corded waistline, as shown.

I claim:

The ornamental design for a dress, substantially as shown and described.

ANNE REBHUHN.
